UNITED STATES PATENT OFFICE.

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

BUTTONHOLE-SEWING MACHINE.

Application filed February 18, 1922. Serial No. 537,381.

To all whom it may concern:

Be it known that I, EDWARD B. ALLEN, a citizen of the United States, residing at Newtown, in the county of Fairfield and State of Connecticut, have invented certain new and useful Improvements in Button-hole-Sewing Machines, of which the following is a specification, reference being had therein to the accompanying drawings.

10 This invention relates to buttonhole sewing machines and has for an object the re-organization of an automatic buttonhole sewing machine more particularly of the type disclosed in my Patent No. 15,324, re-
15 issued April 4, 1922, so that it will operate to cut the buttonhole prior to stitching it.

To this end the clamp-closing mechanism, which is tripped into operation by the starting device, is connected to initiate the operation 20 of the buttonhole cutting mechanism. The buttonhole cutting mechanism embodies a cutter-shaft which operates through suitable cams and connections to cut and spread the buttonhole and trip into action the rapid-
25 feed mechanism which shifts the work-clamp with the cut and spread buttonhole rapidly from cutting to sewing position, whereupon the stitch-forming mechanism is started and sews the buttonhole. At the
30 completion of the sewing operation the rapid-feed mechanism is again thrown into operation and carries the work-clamp with the finished buttonhole rapidly to initial position, in which position the work-clamp
35 is opened and unspread. A safety feature is preferably incorporated to prevent accidental starting of the buttonhole cutting mechanism while the work-clamp is displaced from cutting position.

40 The invention comprises the novel combinations of parts and constructive features hereinafter described and claimed.

In the accompanying drawings, Fig. 1 is a side elevation of an automatic buttonhole sewing machine embodying the invention; the continuously rotating driving pulley for the buttonhole cutting mechanism having been removed from the cutter-shaft to better show various operative parts associated with such shaft. Fig. 2 is a horizontal section through the vertical frame member or standard of the machine; the machine bed and parts thereon being shown in plan. Fig. 3 is a fragmentary rear end elevation of the machine. Fig. 4 is a section on the line

4—4, Fig. 3, showing certain parts of the cutter starting mechanism in elevation. Fig. 5 is a transverse vertical section through the machine bed looking toward the front of the machine. Fig. 6 is a vertical section substantially on the line 6—6, Fig. 5, and Fig. 7 is a fragmentary left side elevation of the machine.

In the specific embodiment of the invention chosen for the purposes of the present disclosure and illustrated in the drawings, the stitch-frame or main-frame of the machine comprises the usual hollow rectangular base 1 from which rises the hollow standard 2 of the overhanging bracket-arm 3 terminating in the head 4 which carries the usual mechanism for the reciprocating and laterally jogging needle 5. The needle-operating mechanism is preferably constructed substantially in accordance with the disclosure of my said patent and includes the usual vertical shaft 6 which is connected at its lower end by gears 7 to the main sewing shaft 8. The vertical shaft 6 is connected by the gears 9 to the needle-bar operating shaft 10 which extends longitudinally of and within the bracket-arm 3 and drives the needle in the well known manner disclosed in said patent.

The needle cooperates with the usual loop-taker mechanism, not shown, to form the overseaming stitches. It is preferred to employ a loop-taker mechanism of the type disclosed in the patent to Allen et al., No. 1,372,473, of March 22, 1921. This mechanism is driven by the shaft 8 and operates wholly below the level of the work; being adapted to form the so-called I. B. H. stitch, as illustrated in said Allen et al. patent.

The work-frame or work-holder is preferably constructed substantially as disclosed in my said reissued patent and in my Patent No. 1,136,388. It comprises the usual lower clamping plates 11 and upper pivotally mounted clamping levers 12 carrying the clamping feet 13; the clamping levers 12 being adapted to be depressed into clamping engagement with the work by movement of the connected rock-shaft sections 14 one of which carries the usual finger-piece 15 and arm 16 which latter extends under the roll 17, Fig. 2, at the front end of the clamp-closing lever 18; Fig. 1, which is pivoted to the standard 2 at 19.

The lower or work-supporting plates 11

of the work-clamp are mounted as usual upon the cross slide-plate 11^a, Fig. 2, to partake of a spreading movement which may be imparted by toggle connections of substantially the form described in my said reissued patent. Such connections comprise the clamp-spreading slide-plates 20, 20' which carry the pins 21 against which are pressed the headed pins 22 carried by the brackets 23 secured to the fulcrum-blocks 24 for the clamp-levers 12. A lever 25 is fulcrumed at 26 to the cross slide-plate 11^a and is pivoted at 27 to a lever 28 pivoted in turn at 29 to the slide-plate 20. The lever 25 is pivoted at its other end to one end of a link 30 which at its other end is pivotally connected at 31 to the slide-plate 20'. The toggle connection may be straightened to spread the clamp by a forward push upon the free end 32 of a lever pivoted at 33 on the plate 20' and having its other end forked to embrace the fulcrum-pin 34 which connects the lever 25 and link 30. A forward push at the free end of the lever 28, by means hereinafter described, unspreads the clamp.

The work-clamp is mounted as usual for longitudinal and lateral motion over the bed of the machine to carry the buttonhole rapidly from cutting to sewing position and return, and to move the work in the desired path during the sewing of the button-hole. The motions of the work-holder are preferably derived from rapid and stitching-feed mechanisms such as disclosed in my said reissued patent. Such mechanisms include the feed-wheel 35 to which the transverse or rapid-feed shaft 36 is permanently connected by the gears 37; the shaft 36 detachably carrying one of a set of interchangeable cams 38 for controlling the period of operation of the stitch-forming mechanism and having a lateral feed-cam groove which in conjunction with selectively controlled mechanism set forth in my said reissued patent may be used to control the side shift movements of the work-holder, in lieu of the side shift cam-groove in the main feed-wheel, as when sewing a button-hole having a smaller eye or other variations in shape from that produced by the action of the side-shift cam in the main feed-wheel.

The permanently connected feed-wheels 35 and 38, when tripped into operation, are first driven at a comparatively high speed by an automatically controlled clutch connection with a continuously running power-shaft 39 which is geared at 40 to the continuously running pulley 41 of the driving device for the stitch-forming mechanism. The rapid-feed clutch embodies the usual driving and driven clutch-elements 42, 43, Fig. 5, on the shaft 36; driving relation being established by movement to the right,

Fig. 5, of the endwise slidable rod 44 carrying the lateral pin 45 and clutch-operating fork 46 which slides the clutch-controlling cone 43' on the shaft 36. It will be understood, particularly from the disclosure of my said reissued patent, that the withdrawal of the cone 43' from the driven clutch-member 43 permits the clutching of such member to the driving element 42 to be accomplished. Projection of the cone 43' toward the driven clutch-element 43 effects the declutching of the parts 42 and 43.

Mounted in the base 1 on the bracket 47 is the continuously rocking bellcrank-lever 48, 49, the forked arm 49 of which embraces a crank 50 on the power-shaft 39. Pivoted side-by-side at 51 on the arm 48 of the bellcrank-lever are the reciprocating bars 52, 53. The rod 52 has connected to its free end a spring 54 which pulls the bar 52 downwardly against the shoulder 55, Fig. 6, on the latch 56 pivoted at 57 to the bed 1. The spring 56' connected at its opposite ends respectively to the latch 56 and to the frame 1 yieldingly holds the latch in supporting engagement with the bar 52. Connected to the free end of the companion bar 53 is a spring 58, Fig. 7, which pulls it upwardly against the seat 59, Fig. 6, on the latch 60 also pivoted at 57 on the bed 1. The bars 52, 53 reciprocate idly when supported by their respective latches 56, 60.

When the latch 60 is withdrawn from the bar 53, the latter is pulled upwardly by its spring 58 and the abrupt shoulder 68, Fig. 5, engages the pin 45 on the clutch-controlling slide-rod 44 and pushes the latter to the right to withdraw the cone 43' from the rapid-feed clutch and thereby effect the coupling of the rapid-feed shaft 36 to the power-shaft 39. During the return movement of the bar 53, the inclined shoulder 69 encounters the pin 45 and causes the bar 53 to be deflected downwardly sufficiently to be engaged by the latch 60 and held in idle position. Similarly, when the latch 56 is withdrawn from the bar 52, the latter is pulled downwardly by the spring 54 and the abrupt shoulder 70 engages the pin 45 and pushes the rod 44 to the left to declutch the rapid-feed shaft 36 from the power-shaft 39; the return movement of the bar 52 carrying the inclined shoulder 71 against the pin 45 which lifts the bar 52 sufficiently to be engaged and supported in idle position by the latch 56.

During the sewing, the connected feed-wheels 35, 38, are driven at a slow speed by the usual stitching feed including the gear 35' on the feed-wheel 35 and a train of gears, not shown, connected with the sewing shaft 8.

The period of operation of the stitch-forming mechanism is controlled by the usual stop-motion device which is constructed substantially in accordance with the

disclosure in my said reissued patent, and embodies the tilting stop-motion lever 72 fixed to the rock-shaft 73 mounted in the bracket 74 and carrying the usual spring-pressed stopping tooth 75. When the lever 72 is tilted to withdraw the tooth 75 rearwardly from the stop-notch 76, Fig. 3, in the stop-cam 77, the pulley 41 is coupled to the shaft 8. When the lever 72 is restored to its vertical position, Fig. 7, the tooth 75 is engaged and lifted by the eccentric portion 78, Fig. 3, of the stop-cam until the stop-notch 76 passes under the tooth 75, whereupon the latter drops into such notch 15 and arrests the motion of the shaft 8. The stop-motion lever 72 is controlled by means of an arm 79 which is fixed to the rock-shaft 73 and is connected by the link 88, 89, to the upstanding lever 81 pivoted at 82 to 20 the bed 1 and carrying a cam-follower 83 which rides on the cam-element 84 on the interchangeable wheel 38. When the follower 83 is encountered by the cam rise 85, Fig. 7, the stop-motion lever 72 is tilted to 25 start the stitch-forming mechanism. When the declivity 86 passes the follower 83 the stop-motion lever 72 is released and is restored to stopping position by the spring 87. The link 88, 89, is in the form of a 30 toggle which may be broken by swinging the handle 90 forwardly to withdraw the follower 83 from operative relation with the cam-wheel 38. It is often desirable to break this toggle to render the starting connection 35 for the stop-motion device inoperative when the machine is being repaired or adjusted.

The lateral arm 91 on the element 89 engages the element 88 and permits the center 92 to drop even with or slightly below a 40 line joining the centers of the connections at the opposite ends of the toggle. The spring-pressed round-nosed pin 88^a, Fig. 2, mounted in the link 88 enters a shallow recess in the side of the element 89 and yieldingly holds 45 the toggle elements in straightened relation.

The buttonhole-cutting mechanism is constructed substantially in accordance with the disclosure of my said reissued patent and includes the usual cutter-levers 93, 94, which 50 are pivotally mounted at 95 on the travelling fulcrum-block 96; the latter receiving its travelling movements from the usual link connection 97 with the cutter advancing and retracting cam 98, Fig. 2, 55 on the cutter-shaft 99. The cutter-shaft also carries the usual cutter-closing cams 100, 101. The cutter-shaft has fixed thereto the driven member or disk 102 of the usual one-revolution clutch device; said 60 disk being radially slotted at 103 to receive the spring-pressed slide-block 104 carrying the clutch-tooth 104. The slide-block 104^a is held in retracted position by the usual latch-plate 105 at the forward 65 end of the clutch-controlling bellcrank-le-

ver 106 fulcrumed at 107 on the bed 1. Clockwise movement of the bellcrank-lever 106, Fig. 2, about its fulcrum 107, withdraws the latch-plate 105 and releases the clutch-tooth 104 on the slide-block 104^a, whereupon the latter is projected outwardly along its slide-way 103 by the spring 108 and into engagement with an internal tooth 108^a, Fig. 3, on the usual continuously running pulley 109. At the completion of a single rotation of the 75 cutter-shaft 99 a lug 104^b on the inner side of the slide-block 104^a engages the cam-edge 110, Fig. 1, on the latch-plate 105 and is pushed inwardly to withdraw the tooth 104 from engagement with the internally 80 toothed driving pulley 109, whereupon the motion of the disk 102 is arrested by the engagement of the lug 104^b with a shoulder 111 on the latch-plate 105. Prior to the completion of the single revolution of the shaft 85 99, the latch-plate 105 is restored to stopping position by means of a cam 112, Fig. 2, formed in the hub of the disk 102 and acting on the follower-pin 112^a depending from the lever 106. 90

When the machine is started, the clamp-closing lever 18 is given a single complete to-and-fro movement by means of a cam-groove 109^a, in the inner face of the continuously rotating pulley 109; the controlling 95 connections for initiating the rocking movement of the lever 18 and holding it out of action being constructed substantially in accordance with the disclosure of my said reissued patent. The rearwardly disposed 100 arm 113 of the clamp-closing lever 18 carries the endwise movable follower-pin 114 which is held in ejected position out of engagement with the cam-groove 109^a in the 105 pulley 109 by the latch 115 pivoted at 116 to the standard 2.

This latch is swung to the right, Fig. 1, to release the pin 114 by the action of the operator in forcing down the starting rod 117 connected to the bellcrank-lever 118, 110 119, also fulcrumed at 116. The arm 119 carries a pivoted catch 120 which engages the pin 121 on the latch 115 and withdraws the latter from the notch in the pin 114, as 115 explained in my said reissued patent. As the arm 18 is depressed to engage the arm 16 and close the work-clamp, the tooth 122 on the link 123 which is pivotally connected at 124 to the arm 113 of the clamp-closing lever, is drawn forwardly and drops down under the influence of the spring 123^a in front of the shoulder 125 on the lateral arm 126 of the cutter clutch-controlling bellcrank-lever 106. The tooth 122 is formed on a plate 127 which is adjustable lengthwise of its carrier 123 and is secured thereto by the screw 128.

During the return or clockwise movement of the clamp-closing lever 18, Fig. 1, the tooth 122 pushes the arm 126 rearwardly and 130

thereby shifts the latch-plate 105 inwardly and releases the clutch-tooth 104 which operates to couple the cutter-shaft 99 to the pulley 109 for one complete revolution.

5 During the revolution of the cutter-shaft the buttonhole cutter levers are advanced and closed to cut the buttonhole. Fixed to the cutter-shaft 99 is a cam 129 in engagement with which is a follower roll 130

10 on the T-shaped lever 131 which is fulcrumed at 132 on the bed 1. The spring 133 holds the roll 130 in engagement with the cam 129. The free end 134 of the lever 131 is disposed closely in rear of the free end 132 of the clamp-spreading lever. During the last half of the revolution of the cutter-shaft 99 and after the buttonhole has been cut, the cam 129 rocks the lever 131 and causes it to push forwardly on the clamp-spreading lever 32, thereby spreading the clamp and opening up the buttonhole-slit for the passage of the needle. Just before the motion of the cutter-shaft is arrested, a cam 135, Fig. 1, on the driven disk 102

15 depresses the lever-arm 136 which is fixed to a transverse rock-shaft 137 to which is also fixed a lever-arm 138 having at its lower end a pin 139, Fig. 6, which enters the slot 140 in the latch 60. By means of this connection, the cam 135 is caused to withdraw the latch 60 from the reciprocating bar 53 and thus throw the rapid-feed mechanism into operation. The spring 141, Fig. 1, connected to the lever 136 and to the bed 1

20 holds the roll 142 on the arm 136 in engagement with the peripheral cam-edge of the disk 102 and restores the latch 60 to latching position.

25 The cutter-shaft 99 also has fixed thereon a cam 143 in engagement with which is the roll 144 on the lever 145 pivoted at 146 to the standard 2. The lever 145 has at its rearward end a lateral extension 145' underlying the link 123. During the first part of the revolution of the cutter-shaft 99 the lever 145 is lifted and operates to lift the link 123 high enough to carry the tooth 122 above the shoulder 125 and permit the cam 112 to restore the bellcrank-lever 106, 126, to initial position in time to arrest the rotation of the disk 102 at the completion of a single rotation. When the link 123 is lifted by the lever 145, the latch-lever 147, Fig. 3, is swung over to the right about its pivot

30 148 by its spring 149 to position its shoulder 150 below and in supporting engagement with the rear end of the link 123. This movement of the latch 147 also positions its extension 151 directly in rear of the pin 152, Fig. 2, on the bellcrank-lever arm 126 and blocks the possible accidental movement of the bellcrank-lever 106, 126, to starting position during the sewing operation.

35 The latch 147 holds the link 123 with its tooth 122 in elevated or ineffective position

so that in case the latch-pin 114 is accidentally released during the sewing the clamp-closing lever 18 will merely perform an idle to-and-fro movement without jamming the parts.

70 The rapid-feed mechanism operates in the usual manner, as disclosed in my said re-issued patent, to carry the work-clamp to sewing position whereupon the cam-rise 85 on the interchangeable cam-element 38 initiates the shifting of the stop-motion lever 72 to running position, thereby starting the stitch-forming mechanism. At the same time, a tripping point 153, Fig. 6, on the inner face of the cam 38 engages and lifts the free end of the lever 154 which, in turn, withdraws the latch 56 from beneath the reciprocating bar 52, thereby throwing the latter into action to declutch the rapid-feed shaft from the power-shaft 39.

80 At the completion of the sewing, the declivity 86 of the cam 84, Fig. 7, passes the follower 83 and allows the stop-motion lever 72 to spring to stopping position and arrest the stitch-forming mechanism. The stop-motion tooth 75 has fixed thereto a lateral pin 155, Fig. 1, which enters a slot 155' in one end of a lever 156 which is pivoted at 157 on the plate 158 fixed to the bracket-member 74. Pivoted at 159' to the other end of the lever 156 is the lower end of a lever 159 having a forwardly projecting tooth 160 and a rearwardly and upwardly curved extension 161 which is yieldingly maintained in engagement with the fixed pin 162 by the spring 163.

85 The elevation of the stopping tooth 75 by the cam-rise 78, when the stop-motion lever 72 springs to stopping position, acts through the rock-lever 156 to lower the lever 159 whereupon the tooth 160 of the latter snaps under the shoulder 164 at the rear end of the arm 165 fixed to the rapid-feed starting rock-shaft 137. When the stopping tooth 75 drops into the stop-notch 76 of the cam 77, the tooth 160 lifts the arm 165 and thereby swings the arm 138 and latch 60 to the right, Figs. 1 and 6, to clutch the rapid-feed shaft to the power-shaft 39 for the return of the work-holder from sewing position to starting position.

90 The work-holder has secured to its rearward corner adjacent the interchangeable wheel 38, Figs. 2 and 7, the rearwardly extending bar 166 the extremity of which is bent to form a cam-incline 167. Pivotally mounted on the standard 2 at 168 is the bellcrank-lever 169, 170, the arm 170 of which is connected to the usual clamp-opening push-rod 171 from which depends the clamp-unspredding arm 172. As described in my said reissued patent, the rod 171 when pushed forwardly engages the arm 173 fixed to the clamp-closing rock-shaft section 14 and pushes such arm forwardly

to open the work-clamp. The lower end of the arm 172 is also caused to engage and operate the clamp-unspreading lever 28.

The arm 169 of the bellcrank-lever has pivoted thereon a lever 174 having a tail piece 175 which is held yieldingly against the stop-pin 176 by the spring 177. Rearward motion of the work-clamp from sewing to cutting position carries the cam incline 167 under the lower end of the lever 174 and lifts the latter, thereby swinging the bellcrank-lever 169, 170, and pushing the rod 171 and arm 172 forwardly to effect a quick opening and unspreading of the work-clamp as near as possible to the end of the cycle of operations of the machine. The simultaneous movement of the work-clamp and rod 171 in opposite directions at the time of the collisions between the members 171 and 173 and between the members 172 and 28, favors the attainment of a quick acting clamp-opening and unspreading mechanism. When the cam-incline 167 passes rearwardly of the lever 174 the spring 178, connected at its opposite ends to the arm 170 and standard 2, restores the parts 169 to 172, inclusive, to initial position. The finished work is now free to be removed from the machine.

Mounted on the side of the machine frame in bearings 179, 180, is a rock-shaft 181 to the rearward end of which is fixed the tappet-arm 182, Fig. 3, which is adapted to engage the arm 183 of the latch 147. Fixed to the forward end of the shaft 181 is a downwardly extending arm 184 the lower end of which is bent forwardly at 185, Fig. 1, to underlie the cam-incline 186, Fig. 5, on the block 187 fixed to the starting rod 117. When the starting rod is pulled downwardly to start the machine, the inclined face 186 of the block 187 engages the extension 185 of the arm 184 and displaces the latter to one side as the block 187 passes said extension, whereupon the extension 185 is restored to a position above the block 187 by action of the spring 184' and operates to latch the starting rod 117 in depressed position.

During the final movement of the rapid-feed shaft 36, the tripping point 188, Fig. 5, on the vertical gear 37 swings the arm 189 outwardly about its fixed pivot 190. The arm 189 engages the tail 191 of the latch arm 184 and swings the latter outwardly to release the starting rod 117 which is drawn upwardly to initial position by its spring 192. Thus, when the starting rod 117 is once pulled down to start the machine, it is latched in its depressed position until the machine has substantially completed its cycle of operations. The swinging of the latch-arm 184 by the tripping point 188 and arm 189 also rocks the shaft 181 and thereby causes the tappet 182 to depress the arm 183 and

swing the latch 147 to the left, Fig. 3, thus releasing the link 123 and permitting it to drop to the position shown in Figs 3 and 4, in readiness to actuate the bellcrank 106, 126, of the cutter-starting mechanism at the beginning of a new cycle of operations. As soon as the tripping point 188 has acted upon the arm 189, the rapid feed is thrown out by the action of the tripping point 153', Fig. 6, upon the lever 154, constituting an element of the clutch-controlling mechanism previously referred to.

Having thus set forth the nature of the invention, what I claim herein is—

1. A buttonhole sewing machine having, in combination, a main frame, stitch-forming mechanism, a work-clamp, means for relatively moving the stitch-forming mechanism and work-clamp to sew about a buttonhole, clamp-closing mechanism including a clamp-closing element and power means for imparting to the latter clamp-closing and return impulses in opposite directions, buttonhole cutting mechanism, and means connected to be operated by said clamp-closing element on its return impulse for starting the buttonhole cutting mechanism prior to sewing.

2. A buttonhole sewing machine having, in combination, stitch-forming mechanism, a work-clamp, a clamp-closing lever, buttonhole cutting mechanism including a starting lever, and a bar connected to the clamp-closing lever for directly engaging and actuating the cutting mechanism starting lever.

3. A buttonhole sewing machine having, in combination, stitch-forming mechanism, a work-clamp, means for relatively moving them to sew about a buttonhole, clamp-closing mechanism including a clamp-closing lever, power means and connections for imparting clamp-closing and return impulses to such lever, buttonhole cutting mechanism including a cutter-shaft, power means and connections including a cutter-tripping lever for establishing driving relation between the power means and the cutter-shaft, and a bar pivotally connected to said clamp-closing lever for directly engaging and operating said cutter tripping lever on the return impulse of the clamp-closing lever.

4. A buttonhole sewing machine having, in combination, stitch-forming mechanism, a work-clamp, means for relatively moving the stitch-forming mechanism and work-clamp to sew about a buttonhole, clamp-closing mechanism, buttonhole cutting mechanism, automatically operated means connected to the clamp-closing mechanism for starting the buttonhole cutting mechanism prior to sewing, means operated by the buttonhole cutting mechanism for rendering the starting connection between the clamp-closing and buttonhole cutting mechanisms ineffec-

tive during the sewing operation, and means for rendering said starting connection effective at the close of the buttonhole making cycle.

- 5 5. A buttonhole sewing machine having, in combination, stitch-forming mechanism, buttonhole cutting mechanism, a work-clamp, a rotary power-driven rapid-feed mechanism independent of the buttonhole mechanism 10 cutting mechanism for relatively moving the work-clamp and stitch-forming mechanism with a continuous motion into and out of sewing relation, a stitching-feed for relatively moving the stitch-forming mechanism and work-clamp during the sewing, means 15 for starting the buttonhole cutting mechanism prior to sewing, and means controlled by the buttonhole cutting mechanism for starting the rapid-feed mechanism to relatively move the stitch-forming mechanism 20 and work-clamp into sewing relation.

6. A buttonhole sewing machine having, in combination, stitch-forming mechanism, buttonhole cutting mechanism including a 25 cutter-shaft, a work-clamp, a rotary power driven rapid-feed mechanism independent of the buttonhole cutting mechanism for relatively moving the work-clamp and stitch-forming mechanism with a continuous motion 30 into and out of sewing relation, a stitching feed for relatively moving the stitch-forming mechanism and work-clamp during the sewing, means for starting the buttonhole cutting mechanism prior to sewing, and 35 a cam on the cutter-shaft and connections for starting the rapid-feed mechanism after the buttonhole has been cut.

7. A buttonhole sewing machine having, in combination, stitch-forming mechanism, 40 a work-clamp, means for moving the work-clamp, clamp-closing means, and clamp-opening means mounted independently of the work-clamp and arranged to be operated by and in a direction opposite to the movement of the work-clamp for opening the work-clamp.

8. A buttonhole sewing machine having, in combination, stitch-forming mechanism, a work-clamp, means for moving the work-clamp, clamp-spreading means, and clamp 50 unspreading means arranged to be operated by and in a direction opposite to the movement of the work-clamp for unspreading the work-clamp.

9. A buttonhole sewing machine having, in combination, stitch-forming mechanism, a work-clamp, means for moving the work-clamp, clamp-closing and spreading means, and clamp-opening and unspreading means 55 arranged to be operated by and in a direction opposite to the movement of the work-clamp for opening and unspreading the work-clamp.

10. A buttonhole sewing machine having, 60 in combination, stitch-forming mechanism,

a work-clamp, a buttonhole cutter, means for moving the work-clamp from buttonhole cutting to sewing position and from sewing to buttonhole cutting position, clamp-closing mechanism, and clamp-opening means mounted independently of the work-clamp and arranged to be operated by and in a direction opposite to the direction of the movement of the work-clamp from sewing to cutting position for opening the work-clamp. 70 75

11. A buttonhole sewing machine having, in combination, stitch-forming mechanism, a work-clamp, a buttonhole cutter, means for moving the work-clamp from buttonhole cutting to sewing position and from sewing to buttonhole cutting position, clamp spreading mechanism, and clamp unspredding means arranged to be operated by and in a direction opposite to the direction of the movement of the work-holder from sewing to cutting position for unspredding the work-clamp. 80 85

12. A buttonhole sewing machine having, 99
in combination, stitch-forming mechanism,
a work-clamp, a buttonhole cutter, means for
moving the work-clamp from buttonhole cut-
ting to sewing position and from sewing to
buttonhole cutting position, clamp-closing
and spreading mechanism, and clamp-open-
ing and unspreading means arranged to be
operated by and in a direction opposite to
the direction of the movement of the work-
holder from sewing to cutting position for
opening and unspreading the work-clamp. 100

18. A buttonhole sewing machine, having, in combination, stitch-forming mechanism, a work-clamp, means for imparting travelling movements to the work-clamp to shift the latter into and out of sewing position, clamp-closing mechanism, an actuating element mounted to travel with the work-clamp, and clamp-opening mechanism including an actuated element connected to be operated by said actuating element during the return movement of the work-clamp from sewing position, said elements being constructed to pass one another idly during the movement of the work-clamp to sewing position. 115

14. A buttonhole sewing machine, having, in combination, stitch-forming mechanism, a work-clamp, means for imparting travelling movements to the work-clamp to shift the latter into and out of sewing position, clamp-spreading mechanism, an actuating element mounted to travel with the work-clamp, and clamp-opening mechanism including an actuated element connected to be operated by said actuating element during the return movement of the work-clamp from sewing position, said elements being constructed to pass one another idly during the movement of the work-clamp to sewing position. 115 120 125 130

15. A buttonhole sewing machine hav- 130

ing, in combination, a frame, stitch-forming mechanism, a work-clamp, clamp-closing means, buttonhole cutting mechanism including a cutter-shaft, a clamp-spreading lever pivoted at a fixed point on the frame of the machine, and means on said cutter-shaft for actuating said clamp-spreading lever after the buttonhole has been cut.

16. In a buttonhole sewing machine, 10 stitch-forming mechanism including a sewing shaft, a work-clamp, a rapid-feed for relatively moving the stitch-forming mechanism and work-clamp into and out of sewing relation, a second shaft with means for 15 driving it independently of the sewing shaft, a stop-motion device for the stitch-forming mechanism, and a rapid-feed starting member connected to be operated by said second shaft prior to sewing and by the stop-motion device subsequent to sewing.

17. In a buttonhole sewing machine, 20 stitch-forming mechanism, a work-clamp, a rapid-feed for relatively moving the stitch-forming mechanism and work-clamp into and out of sewing relation, buttonhole cutting mechanism including a cutter-shaft, a stop-motion device for the stitch-forming mechanism, and a rapid-feed starting member connected to be operated first by said 25 cutter-shaft and subsequently by said stop-motion device.

18. In a buttonhole sewing machine, stitch-forming mechanism, a buttonhole cutter-

shaft, a rapid-feed controlling rock-shaft parallel to said cutter-shaft, a stop-motion 35 device for the stitch-forming mechanism, and a pair of arms on said rock-shaft adapted to be actuated, respectively, by connections with said cutter-shaft and stop-motion device.

19. A buttonhole sewing machine having, in combination, stitch-forming mechanism, a work-clamp, means for relatively moving them to sew about a buttonhole, buttonhole cutting mechanism including a cutter-shaft with means for operating it prior to sewing, a rapid-feed shaft and connections for relatively moving the stitch-forming mechanism and work-clamp into and out of sewing relation, rotary power means, a 50 rapid-feed rotary clutch for establishing and interrupting driving relation between the power-means and the rapid-feed shaft, means on the cutter-shaft and connections for throwing in the rapid-feed clutch prior 55 to sewing to relatively move the stitch-forming mechanism and work-clamp into sewing relation; a stop-motion device for the stitch-forming mechanism, and means connected to the stop-motion device for throwing in the 60 rapid-feed clutch subsequent to sewing to relatively move the stitch-forming mechanism and work-clamp out of sewing relation.

In testimony whereof, I have signed my name to this specification.

EDWARD B. ALLEN.
